UNITED STATES PATENT OFFICE.

GEORGE W. DYARMAN, OF NEW YORK, N. Y.

TIE FOR RAILROADS AND ROAD CONSTRUCTIONS.

1,226,646.

Specification of Letters Patent. Patented May 22, 1917.

Application filed October 6, 1916. Serial No. 124,080.

To all whom it may concern:

Be it known that I, GEORGE W. DYARMAN, a citizen of the United States, and a resident of New York city, in the county and State 5 of New York, have invented certain new and useful Improvements in Ties for Railroads and Road Constructions, of which the following is a specification.

This invention relates to a tie for rail- 10 roads and road constructions which is made up of a plurality of wooden blocks, bound together in such a manner that a tie of great strength is obtained.

In the accompanying drawing:

15 Fig. 1 is a plan of part of a railroad track showing ties embodying my invention;

Fig. 2 a section on line 2—2 Fig. 1 with the rails omitted;

20 Fig. 3, a similar section on line 3—3 Fig. 1, and

Fig. 4, a horizontal section of one of the blocks.

The main body of the tie is composed of a 25 number of longitudinally alined wooden blocks 1 which are connected with each other in a manner hereinafter specified, and which should be of the same height and width, though they may differ in length.

At points set back from the ends of the tie 30 body there extend at right angles thereto, a pair of alined wings, each composed of one or more blocks 2 which are flush with blocks

1, and constitute part of the stringers that 35 support the rails 3. Blocks 1 as well as blocks 2, are provided along each of their upright sides with a longitudinal groove, the 40 grooves of adjoining blocks communicating with each other. These grooves are adapted for the reception of a number of metal bind- 45 ing rods which are preferably of semi-circular shape in cross section, the outer flat sides of the rods, being flush with the sides of the blocks. Two of these rods, designated as 4, are U shaped and extend along the inner

45 sides of blocks 2 and along the sides of the blocks 1 intermediate blocks 2. Four of the rods, designated as 5 are L shaped and extend along the outer sides of blocks 2, and along the ends of blocks 1 protruding be-

yond blocks 2. Opposite rods 4 and 5 are connected to each other, by means of bolts 6, carrying nuts 7, and accommodated within horizontal bores of the blocks. In this way, all of the blocks 1 and 2 constituting a tie are connected to each other in such a manner 55 that they form a unit combining the cushioning properties of wood with the rigid qualities of metal. If desired, the several blocks may be furnished with tongues 8 and grooves 9 at their meeting ends to increase their hold 60 upon each other. So also, a pair of reinforcing bolts 10, carrying nuts 11, may extend longitudinally through the row of blocks 1 above and below bolts 6 respectively.

It is preferred to alternate the double cross 65 ties constructed as described by straight or wingless ties, one of which is illustrated in Fig. 1. This straight tie is composed of a series of longitudinally alined wooden blocks 1, having grooved sides in which straight 70 metal rods 12 are sunk, said rods being connected by bolts 13 passing through the blocks and carrying nuts 14. The straight ties are not only adapted for railroad construction 75 but also for road construction, for which purpose two lines of said ties are set up along the sides of the road, while the space between said lines is filled in with a suitable road bed or pavement.

A tie constructed as described possesses nu- 80 merous advantages:

It permits small wooden blocks and ends to be utilized for making up the tie, thus materially reducing the cost of the same. The tie can be readily disassembled so that 85 any one defective section may be replaced by a new section. Finally, as the tie body is flush with the wings it will, in conjunction therewith, constitute a stringer or rail support which owing to its peculiar shape is not 90 liable to sink into the soil.

I claim.

1. A tie composed of a series of alined wooden blocks having grooved sides, a pair of metal rods engaging said grooves, and 95 bolts connecting said rods and extending through the blocks.

2. A tie composed of a series of alined

grooved wooden blocks, grooved wooden wings extending at an angle to said blocks, a plurality of bent metal rods engaging the blocks and wings, and bolts connecting said 5 rods.

3. A tie composed of a series of alined grooved wooden blocks, grooved wooden

wings extending at right angles to said blocks, a plurality of U shaped metal rods, and a plurality of L shaped metal rods en- 10 gaging said blocks and wings, and bolts connecting opposite rods.

GEORGE W. DYARMAN.
